UNITED STATES PATENT OFFICE.

THOMAS R. PRICE, OF KNOXVILLE, TENNESSEE.

DESIGN FOR A MANTEL.

SPECIFICATION forming part of Design No. 33,138, dated August 28, 1900.

Application filed July 23, 1900. Serial No. 24,615. Term of patent 3½ years.

To all whom it may concern:

Be it known that I, THOMAS REES PRICE, a citizen of the United States, residing at Knoxville, in the county of Knox and State of Tennessee, have invented and produced a new and original Design for Mantels, of which the following is a specification, reference being had to the accompanying drawings, forming a part thereof.

10 Figure 1 is a front elevation of a mantel, showing my new design. Fig. 2 is an end elevation or profile.

The leading feature of my design consists of a main horizontal shelf A, extending across 15 the width of the mantel, a back B, rising above said shelf A, said back being in the main flat and being divided into three faces B', B², and B³ by a mirror-opening C, and an upper shelf D, relatively narrower and lighter than the 20 shelf A and also extending across the width of the mantel, said mirror-opening being sufficiently elongated horizontally to reduce the faces B' and B² to make them vertically elongated, a short shelf E, extending forward from

the faces B' and B², a turned post F, rising 25 from the shelf A to the shelf D in front of each shelf E and varying in diameter and being considerably ribbed and grooved, the back of the mantel rising considerably above the shelf B and having at its middle a symmetrically-curved portion rising higher than the 30 general height of said top and carved or ornamented and having each corner extended upward and laterally in substantially the form of a crescent, with the open portion directed toward the middle of said face B³, said corner being carved or otherwise ornamented.

Having described my invention, what I claim as new, and desire to secure by Letters Patent, is—

The design for a mantel, as herein shown and described.

In testimony whereof I affix my signature in presence of two witnesses.

THOMAS R. PRICE.
